UNITED STATES PATENT OFFICE.

LOUIS MEYERS, OF NEW YORK, N. Y.

BUTTON FOR GLOVES, &c.

SPECIFICATION forming part of Letters Patent No. 317,662, dated May 12, 1885.

Application filed March 9, 1885. (No model.)

To all whom it may concern:

Be it known that I, LOUIS MEYERS, a resident of New York city, in the county and State of New York, have invented an Improved Button for Gloves, &c., of which the following is a full, clear, and exact description, reference being made to the accompanying drawings, in which—

Figure 1 is a face view of a glove having my improved button. Fig. 2 is a face view of a different kind of glove having said button. Fig. 3 is an enlarged bottom view of the button, partly in section, the line *k k*, Fig. 4, showing the plane of section; and Fig. 4 is a side view, partly in section, of the button.

This invention relates to a new construction of button for fastening gloves, umbrellas, shoes, satchels, and the like; and it consists in combining in one button two distinct parts, the one part being a fixed stud, the other a movable eccentric cap, all as hereinafter more fully described.

In the drawings, with reference to Figs. 3 and 4, the letter A represents a stud having a head, *a*, and a neck, *b*. This stud is securely fastened by suitable means, which I need not here describe for they are well known, to a fabric, B.

C is a cap having a projecting loop or eye, *d*, by which it is attached to an elastic band, *e*, or analogous fabric. This cap has an ec-

centric lip, *f*, on its under side, opposite to the side where the loop *d* is attached. When the fabrics B and *e* are to be buttoned together, the cap C is placed over the stud A, so 35 that its lip *f* catches under the head *a*, as in Fig. 4.

For unfastening the button, it is only necessary to press against the cap C, so as to push the lip *f* away from under the head *a*, whereupon the cap can be readily lifted off the stud, or will fall off. If the lip *f* went all the way around on the lower side of the cap, the unbuttoning operation could be performed only with great difficulty, because any motion of 45 the cap C would bring another portion of the lip under the head of the stud.

In Figs. 1 and 2 I have represented my invention as applied to gloves of different kinds; and it is perfectly clear that the invention is 50 equally applicable to other articles than gloves.

I claim—

1. The combination of the stud A, having head *a*, with the cap C, having eccentric lip *f*, substantially as herein shown and described. 55
2. The combination of the stud A, having head *a*, with the cap C, having lip *f* and loop *d*, as specified.

LOUIS MEYERS.
